UNITED STATES PATENT OFFICE.

FLORENCE N. DOTY, OF LOS ANGELES, CALIFORNIA.

PARACHUTE ATTACHMENT FOR AEROPLANES.

Application filed January 7, 1926. Serial No. 79,766.

My invention relates to improvements in aeroplanes and has particular reference to safety devices, for effecting a gradual descent of the aeroplane, in the event that the same should become damaged, or out of control of the pilot.

In accordance with my invention, the sustaining plane of the aeroplane is in the form of an open framework, and the usual fabric covering is omitted. The cloth or other fabric or flexible material is laid upon this open framework, and is securely bound thereto by retaining cables. The fabric is also permanently attached to the open framework by means of attaching cables. The retaining cables have no permanent connection with the plane frame, or other parts of the machine, but are held thereto by holding cable or cables. The plane framework also embodies a trough, at its edge, for receiving the attaching cables, so there will be no liability of these becoming tangled. When folded and retained flat upon the plane framework, the material functions as a covering for or as a portion of the plane, but when released, upon the cutting of the holding cables, the fabric material then functions as a parachute.

In the accompanying drawings, forming a part of this specification, and in which like numerals are employed to designate like parts throughout the same,

Figure 1 is a front end elevation of an aeroplane embodying my invention,

Figure 2 is a plan view of the same,

Figure 3 is a plan view of the sustaining plane,

Figure 4 is a bottom plan view of the same,

Figure 5 is a perspective view of the aeroplane, showing the parachute open,

Figure 6 is a transverse section taken on line 6-6 of Figure 2,

Figure 7 is a similar view taken on line 7-7 of Figure 2, and,

Figure 8 is a perspective view of one of the cutters.

In the drawings, wherein the purpose of illustration, is shown a preferred embodiment of my invention, the numeral 10 designates the fuselage mounted upon the chassis 11. The fuselage is equipped with a tractor 12 and the usual rudders 13 and 14. Rigidly mounted upon the fuselage 10, in the usual manner, are upper and lower sustaining planes 15 and 16, which may be connected

by struts 17. The lower plane 16 is of the usual construction and need not be further described. The upper sustaining plane 15 embodies a rectangular frame 18, which may be formed of metal or any other suitable material. The longitudinal and transverse portions of the frame 18 are U-shaped in cross section, and provide a trough, having its top 19 open and its bottom 20 closed, as more clearly shown in Figures 6 and 7. The opening within the frame 18 is covered by a suitable open material, such as, a wire fabric 21, attached to the inner sides of the frame 18. The open fabric 21 serves to support the combined covering and parachute material, to be described. The numeral 22 designates the combined parachute and plane cover having attaching cables 23 permanently secured thereto at spaced points, the material of the parachute being of a suitable shape to constitute a parachute, when open, as clearly shown in Figure 5. The attaching cables 23 have their lower ends permanently attached to the bottom 20 of the trough like frame 18, as shown at 24. When the element 22 is arranged flat upon the frame 18, its excess material is folded beneath it, as indicated at 25, Figure 6, while the free edges of the same, and the attaching cables 23 are confined within the trough like frame 18, thereby eliminating liability of these cables becoming tangled.

When in the folded position, the element 22 is engaged by holding cables 26, which are passed transversely over the top of the element 22, preferably in lapping relation, as shown in Figure 3. The arrangement provides loops 27, and loops 28, are formed on the inner free ends of the holding cables, although rings may be employed for this purpose.

The numeral 29 designates a retaining cable, which is passed through the loops 27 and 28 and also through eyes 30, attached to the frame 18, preferably at its ends. The retaining cable has its ends secured together, at 31. The several loops 27 and 28, and the retaining cable are located upon the lower surface of the sustaining plane. The number of transverse runs of the holding cables 26, may be varied, as may be found advantageous and the arrangement shown is given for the purpose of illustration.

Means are provided to cut the retaining cable 29, adjacent to the ends or loops 28

of the holding cables 26, such means comprising blades 32, pivoted at 33, and co-acting with stationary notched blades 34, carried by plates 35, which are attached to the frame 18. The retaining cable 29 passes within the notched blades 34. These blades 32 are connected with cables 36 passed about pulleys 37 and adapted to be pulled by a lever or levers 38, to which they are connected. It is desired to have both blades moved simultaneously, for cutting the retaining cable at two points.

The element 22 is formed of any suitable fabric or material, which may be employed in making a parachute and covering the sustaining plane. The term "cable" as employed throughout the specification and claims, is intended to cover any flexible element or cord, which may be made of fibrous material or metal.

In operation, before the retaining cord 29 is cut the element 22 is held flat upon the upper surface of the open plane frame, and with this frame, functions as a sustaining plane. When the retaining cable 29 is cut, the loops 27 and 28 quickly release themselves from the retaining cable and are, of course, free to move upwardly away from the frame 18. When this occurs the element 22 is opened, as shown in Figure 5, and then functions as a parachute, not only to support the aeroplane and prevent too rapid a descent of the same, but also serving to stabilize it, affording the pilot an opportunity to right the machine, if possible.

It is to be understood that the form of my invention, herewith shown and described, is to be taken as a preferred example of the same, and that various changes in the shape, size and arrangement of parts, may be resorted to without departing from the spirit of my invention or the scope of the subjoined claims.

Having thus described my invention, what I claim is:

1. In an aeroplane, a fuselage, an open frame constituting a portion of the sustaining plane, secured to the fuselage, a 50 combined plane cover and parachute ele-

ment adapted to be folded upon the frame, attaching cables permanently securing the element to the open frame, holding cable or cables passed over the folded element, a retaining cable engaging the holding cable or cables, and means to cut the retaining cable.

2. In an aeroplane, a fuselage, an open frame secured thereto, a combined cover and parachute element adapted to be folded upon the frame, attaching cables permanently secured to the element and to the frame, transverse holding cable or cables passed over the folded element and having loops, a retaining cable passing through the loops and attached to the frame, and means to cut the retaining cable.

3. In an aeroplane, a fuselage, an open frame secured thereto, a combined cover and parachute element adapted to be folded upon the frame, attaching cables permanently secured to the element and the frame, separate transversely extending holding cables passed over the folded element and having loops, a retaining cable passed through the loops, and means to cut the retaining cable.

4. In an aeroplane, a fuselage, an open frame secured thereto, a combined cover and parachute element adapted to be folded upon the frame, attaching cables permanently secured to the element and frame, separate transversely extending holding cables passed over the folded element and having loops, a retaining cable passed through the loops, and devices arranged adjacent the forward and rear edges of the frame to cut the retaining cable at a plurality of points.

5. In an aeroplane, a fuselage, an open frame secured thereto and embodying a marginal trough, a combined cover and parachute element adapted to be folded upon the frame, attaching cables permanently secured to the element and frame and adapted to be folded within the trough, and releasable means for retaining the element folded upon the frame.

In testimony whereof I affix my signature.

FLORENCE N. DOTY.
